Primary Examiner — Clint A Samuel(74) *Attorney, Agent, or Firm* — NZ CARR LAW OFFICE(57) **CLAIM**

The ornamental design for a night light, as shown and described.

DESCRIPTION

FIG. 1 is a front perspective view of a night light, showing my new design;

FIG. 2 is a rear perspective view thereof;

FIG. 3 is a bottom perspective view thereof;

FIG. 4 is a bottom perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken line showing in the drawings is included for the purpose of illustrating unclaimed portions of the night light and forms no part of the claimed design.

1 Claim, 10 Drawing Sheets(56)
